PORATION, South Bend, Ind., a corporation of
Delaware

Original application February 16, 1937, Serial No.
126,064. Divided and this application August
25, 1937, Serial No. 160,927

7 Claims. (Cl. 123—179)

This invention relates to starting mechanism for internal combustion engines, and more particularly to starters of the type adapted to be actuated by fluid pressure.

5 This application is a continuation, in part, of my application No. 388,203, filed August 24, 1929.

An object of the invention is to provide engine starting mechanism embodying novel means 10 actuated by the gases generated when a cartridge is fired.

A second object is to provide starter actuating means of the combustible charge type which includes novel means for transmitting the resulting fluid pressure to one of the rotating elements of the engine to be started, such as the crankshaft.

Further objects include the provision of a novel starter which may be employed for starting airplane engines; one which is simple in construction, dependable in operation, and which may be applied as a unit to an engine. The above and additional objects will appear more fully hereafter in the detailed description.

25 One embodiment of the present invention is illustrated in the accompanying drawing, wherein like reference characters indicate like parts throughout the several views, but it is to be expressly understood that the drawing is for purposes of illustration only and is not designed as a definition of the limits of the invention, reference being had for this purpose to the appended claims.

In the drawing—

35 Fig. 1 is a view, in longitudinal section, illustrating a device embodying the present invention;

Fig. 2 is a detailed perspective view of a portion of the motion transmitting means of Fig. 1; and

40 Fig. 3 is a transverse view of the roller clutch. Referring more particularly to Figs. 1 and 2, the starting mechanism constituting the subject matter of the present invention is adapted to be mounted as a unit on the crank case of an aircraft type of engine, a portion of said crank case being diagrammatically shown at 4, and is adapted to be drivably connected to a rotating member of the engine to be started, such as the 45 crankshaft, a portion of the latter being illustrated at 5. The starting mechanism proper includes a motion transmitting structure and a cartridge charge consuming structure, the former being provided with a housing 6 which is substantially L-shaped in section. The lower short

arm of the housing is provided with a flange 7 having openings to receive bolts 8 whereby housing 6 may be connected to the crank case 4.

The upper portion of housing 6 includes a cylinder 9 in which is mounted a piston 10. The cylinder 9 is so designed and constructed as to limit the upward movement of piston 10, for a purpose which will more particularly be set forth hereafter. The piston is drivably connected through a suitable connecting rod 11 to a crank-shaft 12 having journals 13 and 14 which are rotatably mounted in any suitable manner in the housing 6. A gear wheel 15 is drivably connected to, or integrally formed with, the crank-shaft with its axis of rotation concentric with journal 13. A pinion 16 having its axis of rotation located in a vertical plane which is laterally displaced from the common axis of journals 13 and 14 (Fig. 2) meshes with gear 15 and is drivably connected to a barrel 17 which is rotatably mounted as by means of ball bearings 18 in the lower arm of housing 6. An interiorly threaded nut or sleeve 19 is concentrically disposed within barrel 17 and is drivably connected to said barrel by means of a plurality of friction disks 20. A plurality of coil springs 21 are provided to maintain disks 20 in frictional engagement, and a locking ring 22 is preferably threaded into the inner end of the barrel to vary the pressure exerted by said springs on the disks.

30 Mounted for rotary and longitudinal movement within sleeve 19 is a threaded shaft 23 to the outer end of which is secured a nut 24 adapted to engage an annular shoulder 25 provided within said sleeve. The outer end of shaft 23 carries a jaw clutch member 26 adapted to drivably engage a jaw clutch member 27 secured to engine member 5.

35 Means including a metal cup-shaped member 28 and a flexible washer 29 are preferably associated with the inner end of the barrel structure to prevent oil from seeping into the housing 6 from the engine crank case. In the form shown, a rod 30 slidably extends through pinion 16 and shaft 23 to provide means for positively moving jaw 26 out of engagement with jaw 27 in the event that the parts come to rest with said jaws in engagement. The inner end of rod 30 carries a nut 31 which is in engagement with the inner end of shaft 23, and the outer end of said rod 40 slidably extends through housing 6 and is provided with a head 32 to facilitate movement of the rod.

45 Preferably a coil spring 33 having one end thereof anchored to a boss 6a, as at 34, and the

opposite end rigidly connected in any suitable manner to journal 14, is provided for a purpose to be described more fully hereafter. In the form shown the boss 6a is integral with housing 6.

Means are provided to ignite the solid fuel (commonly termed "powder") of the cartridge and to conduct the burning charge and the resulting gases toward cylinder 9, for actuation of the piston 10. To this end there is provided a 10 housing 38 carrying a flange 39 to facilitate attachment of the housing to some stationary support 40 adjacent the pilot's station on the craft in which the invention is installed. Within the lower portion of housing 38 is slidably mounted 15 a bolt structure 41 which includes a firing pin 49. A cartridge to be consumed is inserted into the housing through opening 42 and the bolt mechanism (which is shown in open position) is moved to closed position, thereby advancing the 20 cartridge 51 to the dash line position indicated, this being its firing position. A latch 43 is normally held in a predetermined position by means of spring 44, and when actuated, serves to withdraw detent 52 from the path of the flange of the sleeve 53 which is threaded to the spindle 54 of the bolt structure. This spindle 54 is surrounded by a spring 56 which engages the head 57 of the spindle, and is compressed as the lower end of the spring is carried upward by the advancing base 58 of the bolt structure—the sleeve 53 and the spindle 54 being held by the detent 52, until withdrawal of said detent permits expansion of the spring 56 and consequent propulsion of the floating pin 49 into contact with the percussion fired cap 61 of the cartridge 51, whereupon the combustible charge is ignited, some of the powder being propelled (while approaching the completely consumed state) through the connecting chambers 45 and 46, along with the gases 40 generated by the burning action which takes place in the said chambers. These gases enter cylinder 9, move the piston downward, and finally—after a lapse of time sufficient to allow complete consumption of that portion of the powder which is blown into the conduit 46—the expanding gases escape through exhaust port 47. This time interval for complete powder consumption, incidentally, is itself a controlling factor in determining the velocity of descent of the 50 piston 10; for the pressure attainable by the generated gases is a direct function of the time interval required for complete combustion of the powder charge, and of course the amount of pressure attainable in the connecting chambers 55 45, 46 determines the amount of force exerted on the piston.

To assist the aeroplane pilot in operating arm 43, a rod or flexible cable (not shown) may be connected thereto. When said arm 43 is swung about its pivot against the tension of spring 44, 60 it will allow spring 56 to act upon the firing pin to fire the cartridge in the manner above recited. The resulting actuation of piston 10 produces rotation of gear 15, pinion 16, barrel 17, 65 and the parts therein, the ratio of the gears being such that a single downward movement of the piston is effective to rotate the barrel a number of times. The barrel rotation may be further multiplied by converting barrel extension 16 70 into a combined pinion and clutch, as by interposing overrunning clutch rollers 71 between the outer part of pinion 16 and the inner part 16a (which will remain integral with the barrel) and by extending said inner portion rearwardly 75 through housing 6 to receive a flywheel 12 with a

relatively heavy rim 13 of large diameter, whereby energy will be stored in said massive rim during the down stroke of the piston 10, which energy will then be effective to continue rotation of the barrel 17 independently of the toothed portion of the pinion, until such stored energy is completely used up.

Due to the inertia of shaft 23 and jaw 26 and the threaded connection of said shaft with sleeve 19, the rotation of the barrel results in longitudinal movement of the driven member 23, 26 into driving engagement with the member 27 of the engine to be started; and the rotation thus imparted to the engine causes the latter to be "cranked" and started. As soon as the engine 15 starts under its own power, the inclined teeth of jaw members 26, 27 are effective to return shaft 23 to normal position with the member 26 in non-driving position. In the event that the engine does not start and the parts come to rest 20 with the jaw clutch members in engagement, rod 30 may be actuated to disengage the clutch members.

When the piston reaches its lowermost position the actuating gases pass out the port 47 and 25 spring 33 is then effective to restore the parts to normal position, which position may visually be indicated by pointer 31. It will be noted from Fig. 1 that the piston engages the end portion of the cylinder 9, the latter being so constructed 30 and designed as to operate as a positive stop, thus limiting the upward return movement of the piston and preventing the piston from reaching a top dead center position. From this construction it will be seen that the crank oscillates 35 through an angular distance less than 180°, and the spring returns the piston after a working stroke, to a position such as that indicated in Fig. 2, wherein the vertical center line of the crank-shaft 12 is laterally displaced from the central 40 vertical center line of the piston. In Fig. 2 the normal positions of crank 12 and connecting rod 11 are indicated by dotted lines *a* and *b* respectively.

It will now be apparent that after the energy 45 of the expanding gases has been utilized in driving the piston downwardly, the piston is returned to a proper position to be actuated by a subsequent charge of actuating gases in order to again operate the rotatable members of the 50 starter in the proper direction.

The use of the friction clutch permits jaw member 26 to transmit a substantially predetermined load thereby protecting the parts against damage and permitting the use of lighter parts 55 whereby a light, compact structure is secured.

There is thus provided a novel engine starting mechanism of the fluid pressure type which may be installed on and removed from the engine as a unit. The gases resulting from the burning 60 of the combustible charge are not introduced into the engine cylinder proper, thereby avoiding any possibility of igniting the engine fuel supply. The piston is always returned, after a working stroke, to a proper firing position for a subsequent start. The housing 6 is preferably formed in several readily disassembled sections whereby the parts may be serviced without the necessity for removing the same from the engine.

Various changes may be made in the details of construction and arrangement of the parts, within the limits of the appended claims.

In addition to being a continuation, in part, of application No. 388,203 above identified, this 75

application is also a division of my application No. 126,064, filed February 16, 1937.

What is claimed is:

- 5 1. In a starter for an internal combustion engine, the combination with a driving barrel of a longitudinally movable engine engaging clutch, disposed within said barrel, means including a clutch retracting rod extending through said barrel for withdrawing said clutch from engine engaging position, and barrel driven means independent of and distinct from said rod for moving said clutch to engine engaging position, a flywheel rotatable with said barrel, said barrel having a rearward extension connecting with said flywheel, a prime mover including a pinion surrounding said rearward extension, and an overrunning clutch drivably connecting said pinion with said rearward extension, to transmit torque to said barrel and simultaneously store reserve energy in said flywheel.
- 10 15 2. In a starter for an internal combustion engine, the combination with a driving barrel of a longitudinally movable engine engaging clutch, disposed within said barrel, means for withdrawing said clutch from engine engaging position, and barrel driven means for moving said clutch to engine engaging position, a flywheel rotatable with said barrel, said barrel having a rearward extension connecting with said flywheel, a prime mover including a pinion surrounding said rearward extension, and an overrunning clutch drivably connecting said pinion with said rearward extension, to transmit torque to said barrel and simultaneously store reserve energy in said flywheel.
- 15 20 25 30 35 3. In a starter for an internal combustion engine, the combination with a driving barrel of an engine engaging clutch, disposed within said barrel, barrel driven means for moving said clutch to engine engaging position, a flywheel rotatable with said barrel, said barrel having a rearward extension connecting with said flywheel, a prime mover including a pinion surrounding said rearward extension, and an overrunning clutch drivably connecting said pinion with said rearward extension, to transmit torque to said barrel and simultaneously store reserve energy in said flywheel.

to said barrel and simultaneously store reserve energy in said flywheel.

4. In a starter for an internal combustion engine, the combination with a driving barrel of an engine engaging clutch, disposed within said barrel, means for moving said clutch to engine engaging position, a flywheel rotatable with said barrel, said barrel having a rearward extension connecting with said flywheel, a prime mover including a part surrounding said rearward extension, and an overrunning clutch drivably connecting said part with said rearward extension, to transmit torque to said barrel and simultaneously store reserve energy in said flywheel.

5. In a starter for an internal combustion engine, the combination with a driving barrel of an engine engaging clutch, rotatable by said barrel, means for moving said clutch to engine engaging position, a flywheel rotatable with said barrel, said barrel having a rearward extension drivably connecting with said flywheel, a prime mover including a part surrounding said rearward extension, and an overrunning clutch drivably connecting said part with said rearward extension, to transmit torque to said barrel and simultaneously store reserve energy in said flywheel.

6. In a starter for an internal combustion engine, the combination with a driving barrel of an engine engaging clutch disposed within said barrel, means for moving said clutch to engine engaging position, a flywheel rotatable with said barrel, and means including a prime mover and an overrunning clutch drivably connecting said prime mover with said barrel, to transmit torque to said barrel and simultaneously store reserve energy in said flywheel.

7. In a starter for an internal combustion engine, the combination with a driving barrel of a flywheel rotatable with said barrel, said barrel having a rearward extension connecting with said flywheel, a prime mover including a pinion surrounding said rearward extension, and an overrunning clutch drivably connecting said pinion with said rearward extension, to transmit torque to said barrel and simultaneously store reserve energy in said flywheel.

ROMEO M. NARDONE.
